US00D973638S

(12) **United States Design Patent** (10) **Patent No.:** **US D973,638 S**
(45) **Date of Patent:** **** Dec. 27, 2022**

(54) **EARPHONE**(71) Applicant: **Apple Inc.**, Cupertino, CA (US)(72) Inventors: **Jody Akana**, San Francisco, CA (US); **Bartley K. Andre**, Palo Alto, CA (US); **Jeremy Bataillou**, San Francisco, CA (US); **Daniel J. Coster**, San Francisco, CA (US); **Daniele De Iuliis**, San Francisco, CA (US); **M. Evans**, San Francisco, CA (US); **Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan**, San Francisco, CA (US); **Robert Kerr**, San Francisco, CA (US); **Shin Nishibori**, Kailua, HI (US); **Matthew Dean Rohrbach**, San Francisco, CA (US); **Peter Russell-Clarke**, San Francisco, CA (US); **Christopher J. Stringer**, Woodside, CA (US); **Eugene Antony Whang**, San Francisco, CA (US); **Rico Zörkendorfer**, San Francisco, CA (US)(73) Assignee: **Apple Inc.**, Cupertino, CA (US)(***) Term: **15 Years**(21) Appl. No.: **29/837,327**(22) Filed: **May 4, 2022****Related U.S. Application Data**

(63) Continuation of application No. 29/805,803, filed on Aug. 30, 2021, now Pat. No. Des. 951,235, which is a continuation of application No. 29/777,088, filed on Apr. 2, 2021, now Pat. No. Des. 929,377, which is a continuation of application No. 29/713,433, filed on Nov. 15, 2019, now Pat. No. Des. 915,354, which is a continuation of application No. 29/581,784, filed on Oct. 21, 2016, now Pat. No. Des. 867,325, which is a continuation of application No. 29/530,281, filed on Jun. 15, 2015, now Pat. No. Des. 769,849, which is a

continuation of application No. 29/493,749, filed on Jun. 12, 2014, now Pat. No. Des. 732,008, which is a continuation of application No. 29/453,449, filed on Apr. 29, 2013, now Pat. No. Des. 707,206, which is a continuation of application No. 29/431,563, filed on Sep. 8, 2012, now Pat. No. Des. 681,015.

(57) CLAIM

The ornamental design for an earphone, as shown and described.

DESCRIPTION

FIG. 1 is a front perspective view of an earphone showing the claimed design;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The dashed broken lines in the figures show portions of the earphone that form no part of the claimed design. The dot-dash lines in the figures show boundaries that form no part of the claimed design.
